MOBILE BOOKCASE

Phil Katzman, 11616 Leavenworth Road,
Omaha, Nebr. 68154

Filed Nov. 29, 1965, Ser. No. 88,246

Term of patent 14 years

(Cl. D33—2)

FIG. 1 is a perspective view of the mobile bookcase, showing my new design.

FIG. 2 is an end elevational view thereof, the view from the opposite end being a mirror image thereof; and

FIG. 3 is a top plan view thereof.

I claim:

The ornamental design for a mobile bookcase, substantially as shown.
